UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

DISCONNECTING SWITCH.

Application filed August 11, 1924. Serial No. 731,507.

This invention relates to switches for transmission lines and especially for high potential lines in which the switch is connected directly to the line.

5 The invention is exemplified in the combination and arrangement of parts shown in the accompanying drawings and described in the following specification, and it is more particularly pointed out in the 10 appended claims.

In high voltage disconnecting switches the cost of insulators is an important item in the cost of the switch. The simplicity and alignment of the switch parts and the 15 certainty of operation are very important features. Switches are sometimes operated at very infrequent intervals so that there may be a tendency of the plates to stick, preventing the opening of the switch or interfering with proper closing. It is the 20 object of the present invention to improve some of these conditions.

Fig. 1 shows the side elevation of one pole of a disconnecting switch.

25 Fig. 2 shows the end elevation of a single pole of the switch.

Figs. 3 and 4 are views similar to Figs. 1 and 2 but showing a modified form of the invention.

30 In Figs. 1, 10 and 11 are the incoming lines. Low resistance electrical contact is made between incoming lines 10 and 11 to the switch blades or arms 12 and 13 through the jumpers 14 and also, through a swivel connection 15. The switch arms 12 and 13 are attached rigidly to the rotating insulators 16 and 17. The insulators 16 and 17 are mounted on shafts 18 and 19 which pass through the bearings 20, and which 35 are mounted on a rigid supporting member 21. The shafts are keyed to crank arms 22 and 23 which in turn are connected to crank pins 24 and 25 through connecting rods 26 and 27. The crank pins are connected 40 through an arm 28 to a shaft 29 which is operated by a sheave wheel 30 and chain 31.

In general, the switch is made up of three 45 identical pairs of poles like that shown in Fig. 1, one for each phase, although the elements may be singularly or gang operated for any number of poles. In Fig. 1 the switch is shown in closed position. The incoming lines 10 and 11 may come directly 50 into the switch or may be first dead ended

or the line tension taken with another insulator mounted on the member 21 or near by. In general, however, the construction is such that the average line may be attached 60 directly to the switch, eliminating additional insulators. The two crank arms 22 and 23 are on the same side of the center plane of the switch. When the crank arm 28 is rotated in a clockwise direction as 65 viewed in Fig. 1, the connecting rods 26 and 27 are moved so that the switch blade 13 comes forward and similarly the switch blade or arm 12 recedes, causing the contacts 32 and 33 to separate. The crank arm 70 is rotated through approximately 180 degrees and by proportioning the length of the crank arms and the distance of the crank pins 24 and 25 from the center of the rotating shaft 29, the distance of opening 75 may be controlled.

Where a switch has been in operation sometime, the contact surfaces at 32 and 33 are likely to corrode so that a considerable force may be required, to cause the two 80 arms to separate. In order to minimize this difficulty the crank pins 24 and 25 are so spaced, both radially and angularly, that the two blades will tend to move in the same direction for a short distance before moving 85 in opposite directions. This causes a twisting motion and tends to lower the friction which may be caused by corrosion. This result is accomplished by spacing the crank pins 24 and 25 so that the line through 90 the crank pins and center of rotation make an angle with each other. By placing one crank pin above and one below the center line through the operating shaft 29 and the point of attachment of the connecting rods 95 26 and 27 to the operating arms 22 and 23, it will be seen that as a rotation of the cranks start, the tendency will be to cause rotation in the same direction.

It is very important that a switch remain 100 either open or closed, unless purposely thrown into the other position. The mechanism is so laid out that this feature will be taken care of at the same time, accomplishing the other desirable results. It is 105 evident that if the crank arm 28 with the crank pins 24 and 25 were free to rotate in a clockwise direction, the switch would tend to open with further rotation in a common clockwise direction. In the same manner, 110

if the switch were in a closed position and the operating crank were free to operate in a clockwise direction, the switch would be again closed. This, however, is prevented by the position of the connecting rods 26 and 27 which pass over the top of the operating shaft 29 in either open or closed positions. Any weight then, due to the connecting rods 26 and 27 or to the crank arm 28 will tend to maintain the switch in whichever position it is thrown. If desired, an additional weight may be placed on the connecting rods 26 and 27 or on a crank arm having the same general direction, attached to the shaft or operating sheave 30 and on the same side as the crank arm 28.

Where the switch is used to disconnect a load or to break charging current, it is usually advisable to provide the switch with arcing horns 34 which come in contact first in closing the switch and which will be the last to break contact. These prevent the heavy current carrying capacity members 32 and 33 from being burned by the arcing which would otherwise be established. In opening the switch the arcing horns tend to increase the length of the arc as the arc ascends, tending to cause it to break. To insure that the arcing horns make contact before the contact members are closed and until after contact is broken between the members 32 and 33, they are set in advance of the arms 12 and 13 or the current carrying contacts 32 and 33. As the arms must continue to come together, it is necessary to provide considerable spring in the arcing horns. In some cases the horns themselves may have enough spring, while in others it may be necessary to attach them to the arms by springs 35.

Where the switches operate under sleet conditions, a weather shed 36 is usually provided to keep rain and sleet out of the contact fingers. Entering contact fingers 37 and 38 which form a wide opening provide considerable pick-up for the switch arms so that any slight out of alignment will not interfere with the blade entering the contact fingers properly. Where the currents are light, sufficient current carrying capacity may be obtained through the swivel connection 15 so that the jumpers 14 may be dispensed with. As the crank arms are practically on their center in open and closed positions, a slight amount of angular displacement in the operating crank will affect the position of the switch arms but little. A further advantage is also gained in that the force which must be applied to the operating shaft 29 is comparatively small. This shaft may be in any suitable form. If made in the form of a square, hexagon, or other angular section, no special provision need be made for accurate spacing between switches for different phases as the

crank arm may be slid along the shaft. Since the torsional moment in the shaft is exceedingly small at the start where the frictional force would be greatest, a rather small shaft may be used. This is an advantage as a shaft may be small enough to readily spring along its axis to overcome irregularities in mounting or spring in structure. The operating chain may be replaced by a cable, a flexible band or other suitable means such as a bevel gear, or in some cases the operating crank arm is attached directly to the shaft 29.

In general, however, it is preferable to use a chain or cable which has more than one turn so that it may be anchored definitely at some point in the sheave to prevent gradual creeping under operation. The chain may then be carried down to another drum 50 which will preferably have a smaller diameter so that the crank 51 attached to the drum will have to be given approximately one complete revolution, while the sheave wheel 30 is making one-half a revolution. This insures a low working force on the crank arm and makes it readily possible to provide a stop 52 so that no heavy force will be thrown on the connecting rods or switch parts.

Where high voltages are used it frequently happens that discharges may occur to ground under surges on the system. Unless the disconnecting switch is made with ground clearances, a discharge is likely to occur from the ends of the switch blades or from some part of the disconnecting switch. To obviate this difficulty the switch may be equipped with insulated controls comprising projecting members of conducting material extending from the charged parts and having their extremities covered with dielectric material, as more fully explained in my prior Patent No. 1,521,743, granted January 6, 1925. The tendency to discharge either from the insulator or from the sharp ends of the switch is readily controlled by insulated controls as shown in Fig. 3. These may be used in various forms suitable for the particular conditions. Insulator 40 shows an insulated control ring applied to the cap of one of the rotating insulators, 42 shows a different type of insulated control applied to the other rotating member. In this case the insulated control may be so positioned on the insulator that it will project into the strongest field which would otherwise tend to discharge in either the open or closed position. A discharge from the ends of the open blades are prevented by the control insulators 43 and 44. These control insulators raise the flash-over voltage particularly for high frequency conditions, thereby tending to eliminate discharges at the contact portions of the disconnecting switch. This permits the use of a smaller

insulator for a given factor of safety or tends to eliminate discharges for a given size of insulator or switch.

In Fig. 3 the lead 11 is brought into the switch, almost in line with the axis of the insulator. This condition is likely to exist where the incoming lead drops down to the switch from a higher elevation. In this case a funnel shaped member 45 may be used where the axis of the conductor makes an angle with the insulator to prevent sharp bending. In this case the conductor usually has ample torsional movement or resiliency so that it may be clamped directly to the switch rotating member, insuring good current carrying capacity at minimum cost.

If the axis of the insulator is mounted in a horizontal position, the incoming line may come directly into the insulator in the above manner, although there is considerable tension in the line. The lead 10 is attached to one of the rotating insulators through a swivel connection which has sufficient current carrying capacity.

25 I claim—

1. A disconnecting switch comprising a pair of spaced supports, contact arms extending from said supports toward each other and having their adjacent ends in contact with each other and means for swinging said arms together in one direction and subsequently separating said arms to break contact therebetween.

2. A disconnecting switch comprising a pair of spaced insulated supports, arms extending toward each other from said supports and having cooperating contact members and operating means for said arms arranged to impart a movement to said arms in the same direction to loosen the engagement between said contact members and subsequently to impart relative movement to said arms away from one another to separate said contact members.

45 3. A disconnecting switch comprising a pair of substantially parallel supporting members, arms carried by said supporting members and engaging each other at the ends thereof and means for rotating said members about their respective axes to move said arms into and out of electrical contact with each other, said rotating means comprising crank arms extending from said supporting members at the same side of the plane of the axes thereof and means for simultaneously imparting relatively different movements to said crank arms during one part of their operation and for simultaneously moving said crank arms in the same direction during another part of their operation.

60 4. A disconnecting switch comprising a pair of spaced insulators having their axes substantially parallel with each other, switch arms mounted on said insulators and

having electrical contact with each other, crank arms connected with said insulators and extending laterally therefrom on the same side of the plane of the axes of said insulators, separate links connected with said crank arms respectively and a common crank for operating said links simultaneously in the same direction said links being connected with said common crank at points on opposite sides of dead center position when said switch is closed for imparting relatively different movements to said crank arms at the beginning of a switch-opening operation.

5. A disconnecting switch comprising a pair of insulators having their axes arranged in spaced substantially parallel relation, switch arms supported by said insulators and extending therefrom toward each other, crank arms connected with said insulators and projecting laterally therefrom at the same side of the central plane of said insulators, links connected with said crank arms and a common crank for operating said links, said links having spaced connections with said crank to impart movement to said links in opposite directions at the beginning of the movement of said crank and subsequently to move said links in the same direction.

6. A disconnecting switch comprising a pair of supports, contact members carried by said supports and mechanism, including a crank for rotating said supports, said crank being arranged approximately at its dead center position when said contact members are in engagement with one another.

7. A disconnecting switch comprising a pair of insulators arranged in spaced substantially parallel relation with one another, arms supported by said insulators and having electrical contact members thereon and a crank for rotating said insulators to separate said arms, links connecting said crank with said insulators to separate said arms, said links having connection with said crank on opposite sides of the dead center position of said crank when said contact members are in electrical engagement with each other.

8. A disconnecting switch comprising a pair of spaced insulators having their axes substantially parallel, contact arms carried by said insulators, crank arms connected with said insulators and extending in substantially the same direction from the central plane thereof, links connected with said crank arms and a common crank for operating said links, said crank having separate connections with said links in position to impart movement to said links in opposite directions at the beginning of rotation of said crank to open said switch and to subsequently move said links in the same direction.

9. A disconnecting switch comprising a pair of contact members, means for opening and closing said members and means normally tending automatically to move said members to either open or closed position when they are slightly displaced from said respective positions.
10. A disconnecting switch comprising a pair of contact arms, a crank for operating said arms, oppositely extending links connected with said crank and a stop for said links to permit the weight of said crank and links to automatically retain said switch in either open or closed position.
- 15 11. A disconnecting switch comprising a pair of contact members, operating means for said members and a supporting stop for said operating means to support said operating means in position to require lifting thereof to move said contact members out of either open or closed position.
- 20 12. A disconnecting switch comprising a pair of contact members, a shaft for operating said contact members, a crank mounted on said shaft, links extending in opposite directions from said crank and means connecting said links with said contact members, one of said links being arranged to rest upon said shaft and support said crank when said switch is in open position, while the other link rests upon said shaft to support said crank when said switch is in closed position.
- 25 13. A disconnecting switch comprising a pair of insulators having their axes arranged in spaced substantially parallel relation to each other, contact members supported by said insulators and extending therefrom toward each other, crank arms connected with said insulators and projecting on the same side of the central plane thereof, a transverse shaft disposed between the axes of said insulators, a crank secured to said shaft, links extending in opposite directions from said crank and having the ends thereof connected with said crank arms, said links having spaced connections with said crank and arranged to permit said links to alternately engage said shaft when said crank is rotated through approximately 180 degrees, the weight of said links and crank operating to retain said crank at the limits of its rotation.
- 30 14. A disconnecting switch comprising a supporting member, a pair of insulators having pins journaled in said supporting member in spaced parallel relation, switch arms mounted on said insulators, conductors having swivel connection respectively with said insulators; contact members carried by said switch arms and means for rotating said insulator pins to move said switch arms together in one direction during the beginning of an opening operation of said switch and subsequently to move said arms simultaneously in opposite directions to separate said contact members.
- 35 15. A disconnecting switch comprising a pair of supporting insulators, separate switch arms mounted on said insulators rotating means each movable through a limited angular amount for operating said switch arms respectively, a common crank for actuating said rotating means, separate links for connecting said crank with said respective rotating means, and a common stop for cooperating with said links to limit the movement of said crank when said switch arms have moved through the range of their movements.
- 40 16. A disconnecting switch comprising a member movable to two limiting positions for opening and closing said switch, a sheave for operating said member, a crank for operating said sheave, means for limiting movement of said crank to approximately 360 degrees and connecting means for moving said member through its complete range of movement for a complete operation of said crank.
- 45 In testimony whereof I have signed my name to this specification on this 6th day of August, A. D. 1924.
- ARTHUR O. AUSTIN.
